**IGNITER ASSEMBLY FOR STOKER-FIRED
HEATERS AND FURNACES**
John L. Margetts, 2182 Berkley Ave.,
Salt Lake City, Utah 84109
Filed Oct. 11, 1965, Ser. No. 494,841
8 Claims. (Cl. 110—45)

This invention relates to stoker-fired, coal burning heaters and furnaces, and is particularly concerned with igniter means for them.

There has long been a need for a satisfactory igniter means that will, on demand, initiate combustion of coal and/or other solid fuels fed into the retort of a heater or furnace. As a result, there have been a number of systems developed to ignite solid fuels. Some of these, such as that shown in U.S. Patent No. 2,237,237, granted April 1, 1941, require a supply of gas for a gas burner that is ignited through a pilot burner regulated by an electrical control system. The torch thus formed is used to ignite the solid fuel. Others, such as that shown in U.S. Patent No. 2,738,742, granted March 20, 1956, simply use an electric heating element, having a control circuit to regulate its operation, placed in direct contact with the solid fuel.

However, a gas supply is not always available, nor desired, for use with an igniter means, and heating elements placed in direct contact with solid fuel frequently become overheated, and burn out, because the heat they generate is not dissipated quickly enough and/or because of the intense heat created as the fuel around them burns.

It is an object of the present invention to provide a long-lasting igniter means that will, upon demand, automatically initiate combustion of the solid fuel used in a stoker-fired heater or furnace.

The principal feature of the invention is a special insulated tuyere incorporating an electric heating element and forming a portion of the tuyere ring of the heater or furnace retort. Combustion air moving past the special tuyere transfers heat to fuel in the retort and prevents any heat accumulation sufficient to burn-out the heating element. The insulation on the special tuyere prevents heat dissipation through adjacent tuyeres and localizes heat at its source so that it can be efficiently transferred, through conduction to pieces of coal contacting the special tuyere, and, by convection with the entering combustion air.

There is shown in the accompanying drawings specific embodiments of the invention representing what are presently regarded as the best modes of carrying out the generic concepts in actual practice. From the detailed description of these presently preferred forms of the invention, other more specific objects and features will become apparent.

In the drawings:

FIG. 1 is a side elevation view, partially broken away to show the retort and stack of a stoker-fed heater embodying the invention;

FIG. 2, an enlarged, fragmentary, perspective view of the portion of the tuyere ring including the special tuyere of the invention;

FIG. 3, a top plan view of the special tuyere;

FIG. 4, an end elevation view of the special tuyere;

FIG. 5, a vertical section taken on the line 5—5 of FIG. 3;

FIG. 6, a schematic wiring diagram;

FIG. 7, a side elevation view of another embodiment of special tuyere with the retort bowl of a heater shown fragmentarily in vertical section; and

FIG. 8, a view in vertical section taken on the line 8—8 of FIG. 7.

2

Referring now to the drawings:

In the embodiment of the invention illustrated in FIGS. 1—5, a special tuyere 10 forms a portion of a tuyere ring of a retort 11 in a heater shown generally at 12.

Coal is fed in customary manner upwardly through the retort from a tube 13 having the usual feedscrew or other conveyor means therein.

Air is supplied to the retort, also in customary manner, from a plenum chamber 14. The air is forced through an opening 15 between the standard tuyeres forming the upper edge of retort 11 and an outwardly flared, upwardly extending end of tube 13, that forms a retort bowl 16. Spacers 16a, FIG. 1, located at intervals around the retort bowl hold the bowl and tuyere ring separated.

Insulation 17, shown best in FIGS. 4 and 5, holds special tuyere 10 in place while insulating it from the tuyere ring.

The special tuyere 10 is constructed to replace a conventional tuyere and to interlock with conventional tuyeres 18 and 19 adjacent thereto in the same manner as the usual tuyere it replaces. Thus, the special tuyere 10 shown in FIGS. 1—4 includes an outer shell 20 made of cast iron containing at least one percent chromium, or of other good heat conducting but long wearing materials. A central bore 21 is provided within the shell, and a cartridge-type heater element 22 is positioned tightly within bore 21. The lead wires from element 22 trail out the bottom of the bore for connection in a temperature responsive control circuit. In practice, a cartridge-type heating element such as that disclosed in U.S. Patent No. 2,831,951, issued April 22, 1958, to George B. Dislodge has been found quite satisfactory for the purpose.

A lug 23 that protrudes from one side of shell 20 is adapted to slide into a groove provided therefor in tuyere 19. Similarly, groove 24 formed on the other side of shell 20 is adapted to receive a lug protruding outwardly from tuyere 18. Thus interlocked, the tuyeres 18 and 19, together with the remainder of the standard tuyeres and the special tuyere 10, form the ring that serves as the upper peripheral edge of the retort.

Layers of insulating material 25 and 26 at opposite sides of shell 20 prevent undesired dissipation of heat from shell 20 to the adjacent standard tuyeres 18 and 19.

In operation, a conventional thermostat 27, FIG. 5, acting in response to a drop in atmospheric or room temperature closes the control circuit to initiate operation of a motor 28 that powers the conveyor means within tube 13 to supply coal to the firebowl. A separate motor and fan unit can be employed, or if desired, the same motor may supply the power to drive a fan providing pressurized combustion air to the firebowl, in the manner fully disclosed in my copending application Ser. No. 469,813, filed July 6, 1965.

If the temperature within the exhaust stack opening 29 of the furnace, FIG. 1, is below a predetermined minimum, for example 130° F., the movable contact of a temperature responsive element 30, FIGS. 1 and 5, positioned to have a temperature responsive member within the stack, will close and complete the circuit to the cartridge-type heater element 22. This energizes the heating element and heats up the surrounding shell 20. Insulation layers 25 and 26 prevent any significant heat transfer from special tuyere 10 to adjacent tuyeres 18 and 19, and the heat is localized in the vicinity of the special tuyere.

The air from plenum chamber 14 that passes through the opening 15 between the standard tuyeres and the retort bowl carries heat away from the special tuyere and

into the coal. As the coal is fed upwardly through the firebowl, pieces thereof are constantly moved into engagement with the special tuyere, and the entering combustion air also directs heat created by the burning of that coal ignited by direct contact with the special tuyere toward the center of the retort. This prevents a heat build-up in the vicinity of the special tuyere that will cause the heater element 22 to burn out. If the temperature in the stack is at or above the predetermined minimum, the contact of temperature responsive element 30 will remain open and the heating element 22 will not be energized. Of course, if the stack temperature is at the predetermined minimum there will already be a fire in the retort and it will not be necessary for the heating element to operate.

In FIGS. 6 and 7, I show another form of igniter unit of the invention. This embodiment also includes a shell 31 of heat conductive, strong material such as cast iron having at least one percent chromium, with a groove 32 in one side and a lug 33 on the other to facilitate interlocking with conventional tuyeres. However, in this instance, the shell includes an upper head portion 31a, a depending lip 31b, and a lower body portion 31c. The lip 31b is adapted to rest on the edge of tuyere bowl 34, shown fragmentarily in section, with only a layer of insulating material 35 separating them. As in the previously disclosed embodiment, insulating layers 36 and 37 at the sides of the special tuyere limit heat transfer from the special tuyere to the adjacent standard tuyeres. Also, as in the previously disclosed embodiment a cartridge type heating element 38 is used, but, instead of extending through the lower portion of the shell the heating element extends therewith into a bore 39 formed in the upper head portion 30a. With this arrangement the air passing between the igniter unit and the tuyere bowl 34 constantly passes over and cools both the lower body portion 31a of shell 31 and the lower portion of the cartridge heating unit 38. The air then passes through a bore hole 40 through the depending lip portion 31b and into the retort. In so doing it carries heat radiating from the upper head portion 31a of shell 31 and from the burning coal in contact with the shell toward the center of the firebowl, thus preventing a destructive heat accumulation at the heating element. The cooling effect of the air can be regulated merely by changing the size of bore hole 40.

Whereas there is here illustrated and specifically described certain preferred constructions of apparatus which are presently regarded as the best modes of carrying out

the invention, it should be understood that various changes may be made and other constructions adopted without departing from the inventive subject matter particularly pointed out and claimed herebelow.

5 I claim:

1. An igniter assembly for stoker-fired heaters and the like comprising a shell of heat conducting, long wearing and fire resistant material, said shell having means thereon adapted to interlock it between tuyeres of a heater; a layer of insulating material on each side of the shell that is adapted to be in engagement with an adjacent tuyere; and an electrically energized heating element extending into said shell.
2. The igniter assembly of claim 1, wherein the shell is of cast-iron.
3. The igniter assembly of claim 1, wherein the shell is shaped as a tuyere and is adapted to form a portion of a retort of a heater.
4. The igniter assembly of claim 1, wherein the heating element is an elongate cartridge-type heater.
5. The igniter of claim 4, wherein the cartridge-type heater extends upwardly into the shell through a bottom portion thereof.
6. The igniter of claim 4, wherein the cartridge type heater extends upwardly past a bottom portion of the shell and into a top portion.
7. In combination, a stoker-fired heater having a retort including an outer ring of tuyeres; a coal-feed tube through which coal is fed upwardly to the retort; an electric cartridge-type heater element in one of said tuyeres; means insulating said one tuyere from the tuyeres adjacent thereto; means for supplying air to said furnace interior of said ring of tuyeres; and circuit means for energizing said heater element on demand.
8. The combination of claim 7, wherein the circuit means includes a thermostat responsive to room temperature, and a temperature responsive element responsive to the temperature in an exhaust stack of the furnace.
